[57] CLAIM

The ornamental design for coffee pot holder, as shown and described.

DESCRIPTION

FIG. 1 is a top plan view of a coffee pot holder showing our new design;

FIG. 2 is a front elevational view thereof;

FIG. 3 is a bottom plan view thereof;

FIG. 4 is a left side elevational view thereof;

FIG. 5 is a back view thereof;

FIG. 6 is a right side elevational view thereof; and,

FIG. 7 is an isometric view of our design, showing the coffee pot in phantom.

The broken line showing of a coffee pot in FIG. 7 is for illustrative purposes only and forms no part of the claimed design.
